Horace Prindle

UNITED STATES PATENT OFFICE.

HORACE PRINDLE, OF SPAFFORD, NEW YORK.

IMPROVED WASHING-MACHINE.

Specification forming part of Letters Patent No. 43,865, dated August 16, 1864.

To all whom it may concern:

Be it known that I, HORACE PRINDLE, of the town of Spafford, in the county of Onondaga and State of New York, have invented a new and useful Improvement on Washing-Machines; and I do hereby declare that the following is a full, clear, and exact description of the construction and operation of the same, reference being had to the annexed drawings, making a part of this specification, in which—

Figure 1 is a side elevation, and Fig. 2 a sectional view.

My aim is to furnish a washing machine which shall be simple in its construction, easily worked, not liable to get out of repair, and which can be furnished at a small expense.

To enable others to make and use my invention, I will proceed to describe its construction and operation.

My washing-box A may be made of any convenient size, and placed upon suitable legs, (represented in Fig. 1 by the letters *a a.*)

The slanting end of my box B, I make with corrugations *b b*, which can be used as a wash-board.

In the lower portion of my washing-box I place the rollers *c c*, which have spindles or bearings, which spindles revolve in proper holes in said box and constitute a semicircle.

The rubber D, I make of semicircular form, corrugated upon its convex side, which corrugations come in contact with the rollers during the operating of the machine. The rubber is provided with handles *H H*, and two standards, *R R*, fastened to the center of the rubber, which pass through a roller E at the top of the washing box and revolve with the rubber. The standards *R R*, passing through slots in the roller E, readily adjust the rubber D in its upward and downward movements without that resistance which would obtain were the roller E placed in guides or grooves. The resistance to the rubber in its action upon the clothes to be washed is, by reason of the revolving roller E and standards *R R*, always in a perpendicular position to the slots in the roller.

What I claim as my invention is—

The construction of a washing-machine provided with the adjustable rubber D, when combined with the standards *R R*, roller E, provided with slots to receive said standards, and the corrugated end B, in the manner and for the purpose herein specified.

HORACE PRINDLE.
